UNITED STATES PATENT OFFICE.

BENJAMIN WOLHAUPTER, OF NEW ROCHELLE, NEW YORK.

RAIL-ANCHOR.

1,344,015.

Specification of Letters Patent. Patented June 22, 1920.

Application filed August 1, 1918. Serial No. 247,802.

To all whom it may concern:

Be it known that I, BENJAMIN WOLHAUPTER, a citizen of the United States, residing at New Rochelle, in the county of Westchester and State of New York, have invented certain new and useful Improvements in Rail-Anchors, of which the following is a specification.

This invention relates to the subject of rail anchors and primarily has for its object the construction of these devices with maximum structural strength and bearing area, but with a minimum expenditure of metal.

The invention, therefore, fundamentally involves a desirable conservation of metal in the manufacture of rail anchors, as well as an advantageous distribution of the metal in shaping the device, whereby increased strength is obtained by such distribution with the use of a minimum amount of metal. Accordingly, the invention is intended to satisfactorily meet a most important consideration in the manufacture of rail anchors, that is, a reduction in the weight of such devices by the saving of unnecessary metal, so that the anchor may be more cheaply made and handled, and a considerable reduction in manufacturing costs effected.

Other important and practical objects are attained by providing a rail anchor construction having structural characteristics effectually meeting the exacting track conditions imposed thereon. Certain of these characteristics are essential in an ideal rail anchor and are embodied in the present invention. One of these characteristics or features is that the device must be so constructed and arranged that it may have an extensive bearing against the tie in order that the latter may become a substantial and firm abutment to resist, through the medium of the anchor, any longitudinal movement of the rail. At the same time the anchor must not present any sharp edges which will have a tendency to cut into or rupture the fibers of the tie.

A further requirement of an efficient rail anchor is that it must present a relatively large bearing area to the rail so that a firm and substantial connection can be made between the anchor and the rail, whereby, upon being placed in position on the rail, the anchor becomes substantially a rigid

part thereof so that under ordinary service conditions it will be incapable of independent movement.

These practical and necessary requirements and features in a rail anchor are realized and embodied in the present invention which therefore contemplates the provision of a rail anchor construction having the desirable characteristics of maximum contact and bearing area with minimum weight, and maximum structural strength.

Further, in connection with the feature of providing an anchor having a minimum amount of metal, it is to be observed that it is proposed to so distribute the metal in the device as to obtain an anchor having a greater load-carrying and force-resisting capacity than a rectangular or round shape of bar of the same weight commonly used in making structures of this kind.

The present invention also provides a specific form or structure which when applied to the rail, has peculiar and efficient means for locking the anchor to the rail.

With the above and other objects in view, which will more readily appear to those familiar with the art as the nature of the invention is better understood, the same consists in the novel combination, construction and arrangement of parts hereinafter more fully described, illustrated and claimed.

While the invention is necessarily susceptible of embodiment in different structural formations, without departing from the spirit or scope thereof, certain preferred and practical forms are shown in the accompanying drawings, in which:—

Fig. 1 is an elevation of a rail anchor constructed according to the present invention, in its initial position on the rail flange, and showing by dotted lines the distortions produced by driving the anchor onto the rail flange.

Fig. 2 is an end elevation of the anchor shown in Fig. 1, also showing by dotted lines the distorting effect to the rail flange when the anchor is driven tightly thereon.

Fig. 3 is a top plan view thereof.

Fig. 4 is a diagrammatic view illustrating the general cross-sectional shape of the anchor, and illustrating the redistribution of metal from a bar of flat section into a bar of channel formation to obtain the structural strength.

Fig. 5 is an end view of a modified shape of bar which may be used in making the anchor.

Fig. 6 is an elevation of a rail anchor somewhat similar to Fig. 1 but having the end portions thereof tapered since the strains are less at these points than in the body of the anchor.

Similar references designate corresponding parts throughout the several figures of the drawings.

In carrying into practical effect the distinctive feature of the present invention that provides for a reinforced rail anchor structure, which, while relatively light in weight has a materially augmented load-carrying and force-resisting capacity, it is proposed to utilize as the fundamental principle of construction a channel bar distribution of metal. This distribution provides a rail anchor body having a relatively flat vertical web with laterally offset terminal flanges projecting from one side of the web, thus giving to the anchor the strength and rigidity of a channel bar distribution of metal, and at the same time providing a relatively large and firm bearing area for engagement with the rail and with the tie.

In Fig. 4 of the drawings appears an illustration graphically demonstrating the distribution of metal utilized in making the present invention and also demonstrating the mechanical fact that when a rectangular beam is placed under load, the fibers on one side are placed under tension while those on the opposite side are placed under compression, the fibers midway between are neutral, that is carry no load and this location is termed the neutral axis. From this view, it will be observed that the points *a*, *b*, *c*, and *d* represent a rectangular beam, while the horizontal line *x*—*x* designates the neutral axis thereof. By taking the metal indicated as *M* near and above the neutral axis *x*—*x*, and placing it at the top of the bar as indicated at *M'*, and by taking the metal *N* near and below the neutral axis, and placing it at the bottom of the beam or bar as indicated at *N'*, the same will be placed where it will carry a very substantial load, whereas in its former location it was neutral or carrying practically no load. Thus, in the present channel form of bar the same amount of metal will carry a much greater load than a rectangular bar of the same cross-sectional area, and conversely, a channel bar can be made to carry the same amount of load as a rectangular bar with very much less metal. At the same time, the advantage of providing relatively wide upper and lower chords on the bar is to give a much wider bearing area on the rail than would be possible with the original rectangular beam, while at the same time also giving

a wider bearing surface for abutment 65 against the tie.

For the purpose of illustrating the foregoing principles of construction in a rail anchor, reference may be made to Fig. 1 of the drawings which shows a rail anchor 70 adapted to be forcibly driven on the wedge-like rail flange, and securely held in position thereon by the spring gripping force produced through the distortion of the spring clip portion thereof, and by the pressure on 75 the edge of the rail flange, when the anchor is forced into place. Referring specifically to the form of construction shown in Fig. 1 it will be noted that the channel shape, of which the anchor body is formed, is designed generally as 1, and presents a relatively wide and flat bearing face 2 at one side for abutting against the tie *T*, and as shown, essentially includes a clip portion 80 designated generally as 3, which is preferably though not necessarily resilient or springy, and a rail-base engaging member 4 which extends beneath the base of the rail and engages therewith to effectively prevent the lateral displacement of the anchor after 85 it is once in place.

The clip portion 3 of the anchor is of substantially circular or loop formation and the squared-off end 5 thereof is adapted to have a flat bearing engagement with the inclined upper face of the rail flange, while the other end of the loop which is adapted to receive the outer edge of the rail flange is provided with a relatively flat rail-flange engaging face 6 lying substantially in line 95 with the lower face of the rail base. This particular formation of the clip portion 3 therefore provides a relatively stout and substantial rail engaging part for the anchor which will grip the rail flange with increasing tenacity as the entire anchor is shifted laterally as the result of a hammer blow or the like, to thus securely fasten the anchor to the rail, as will hereinafter more fully appear.

From its loop formation to provide the clip, the body of the anchor 1 as at *a* slants downwardly from the inner edge of the relatively flat flange-engaging face 6 to a suitable point or bow and from there is inclined upwardly as at *a* toward the edge of the other rail flange, whereby the free end of the anchor body, designated as 7, may have a bearing engagement with said other rail flange. Thus, it will be observed that the bearing points 5, 6 and 7 of the anchor on the bar form a scalene triangle, and the tail part of the anchor is bowed to admit of a powerful spring tension action.

It will now be apparent that forcing the 125 same in the direction of the arrow in Fig. 1 onto the rail, that is transversely thereof, causes a leverage action in the device, the

fulcrum of the lever being at the point 5 where the free end of the clip bears directly upon the upper inclined face of the rail flange. That is to say, the transverse movement of the anchor with respect to the rail, in conjunction with the wedge shape of the flange thereof, and the alternate disposition of the bearing points 5, 6 and 7, produces a leverage action in the anchor which increases as the device is driven farther onto the rail flange and puts the anchor under a tension so great that the edge of the rail flange lying between the ends of the clip is distorted upward as indicated by the dotted line R in Fig. 1, and at the same time the loop of the clip 3 becomes distorted as indicated by the dotted lines 3^a, and the lower base engaging portion 4 of the anchor also becomes distorted as indicated at 4^a, all of which contributes to provide a most secure and effective locking engagement between the anchor and the rail.

A modified shape of anchor body is shown in Fig. 5 of the drawings from which it will be observed that instead of distributing the metal in the form of a true channel bar such as shown in Fig. 4, a structural shape having the modified channel distribution of the "bulb angle" may be employed. In this formation a relatively thin upper flange 8 is provided to conserve the relatively broad bearing engagement between the anchor body and the rail, while the chord 9 has the metal more concentrated in bulb formation which has special advantages under some conditions of use.

Fig. 6 of the drawings shows a modified anchor of the same type shown in Fig. 1. That is, the structure shown in this figure involves the same channel bar type of anchor body with a holding clip and gripping portion, and a resilient rail-base engaging lever arm. However, in this particular instance it is proposed to further lighten the bar and save metal by tapering the ends of the anchor as indicated at 10 and 11, since at these points the anchor is subjected to considerably less strain than at any other point in its length.

Other modifications and adaptations of the channel distribution of metal may of course be resorted to, and it will be understood that changes in the form, proportion and minor details of construction may be resorted to for the purpose of attaining these ends without departing from the principle of the invention or scope of the appended claims.

I claim:

1. A rail anchor having at one end a loop, the upper part of which engages the top of the rail flange and the lower part of which is provided with a face lying in substantially the same plane with the bot-

tom of the rail and arranged to exert upward flexing pressure on the edge of the rail flange.

2. A rail anchor comprising a bar having flat faces respectively engaging the top face and under edge of one rail flange, and an inclined part engaging the under portion of the opposite flange.

3. A rail anchor including a body having a holding arm for engaging one rail flange, and a flexible loop for embracing the other rail flange, said loop being provided at the terminals thereof with flat rail flange engaging faces, one of which faces is disposed in a plane parallel to the bottom of the rail and the other of which is disposed at an angle thereto, whereby as the anchor is driven laterally on the rail the rail flange tangentially enters the loop and is thereby distorted upwardly with the angularly disposed terminal face of the loop acting as a fulcrum.

4. A rail anchor of channel formation adapted to be applied to the rail with its web perpendicular to the rail bottom and comprising a looped member embracing one rail flange and having an arm extending from the lower portion thereof for engagement with the opposite rail flange, said anchor being subject to spring tension when moved transversely on the rail base.

5. A rail anchor of channel formation placed vertically to the rail base whereby the side of the web bears against the tie abutment.

6. A rail anchor of channel formation placed vertically to the rail whereby the top and bottom chords sustain the strains due to its application, and the vertical web forms a surface for the abutting tie.

7. In a rail anchor, an anchor body having a plurality of load-carrying chords integrally connected, a face of the connecting member engaging an abutment.

8. A rail anchor having a body of channel formation and adapted to be applied to the rail with its web perpendicular to the rail bottom.

9. A rail anchor having a body portion of channel formation and adapted to be applied to the rail with its web perpendicular to the rail bottom and also having rail engaging means.

10. A rail anchor having a body portion of channel formation and adapted to be applied to the rail with its web perpendicular to the rail bottom and also having rail base engaging means.

11. A rail anchor having a body portion of channel formation and adapted to be applied to the rail with its web perpendicular to the rail bottom and also having rail flange engaging means.

12. A rail anchor including a single tie-

abutting body having reinforcing elements projecting to one side only, and rail engaging elements.

13. A rail anchor including a single tie-abutting body having reinforcing flanges at its edges, projecting to one side only, and provided with rail engaging means.

14. A rail anchor including a single tie-abutting body having a channel bar distribution of metal throughout, and provided with rail engaging means.

15. A rail anchor including a spring bar of channel formation and adapted to be applied to the rail with its web perpendicular to the rail bottom, and also having rail engaging means.

16. A rail anchor including a bar consisting of a relatively thin web adapted to be applied to the rail with its web perpendicular to the rail bottom and flanges connected by said web and projecting from one side thereof, and said bar being provided with rail engaging means.

17. A rail anchor including a tapering bar of channel formation having flat rail and tie engaging faces.

18. A rail anchor including a bar having a channel formation and tapering toward its ends, said bar having flat rail and tie engaging faces.

19. A rail anchor including a bar having a channel formation of graduated depth and provided with flat rail and tie engaging faces.

20. A rail anchor including a bar of channel formation of graduated depth toward its ends, and provided with flat rail and tie engaging faces.

21. A rail anchor including a rail engaging clip, having a channel formation and tapering in depth toward its ends, and provided with flat rail and tie engaging faces.

22. A rail anchor consisting of a single tie-abutting body of channel formation and provided with upper and lower clamping jaws.

23. A rail anchor consisting of a single tie-abutting body of channel formation

adapted to be applied to the rail with its web perpendicular to the rail bottom, and one end of which body clampingly engages the top and the other end of which engages the bottom of the rail flange.

24. A rail anchor including a single tie-abutting body of channel distribution of metal throughout and having a gripping jaw at one end.

25. A rail anchor comprising a resilient clip of channel formation.

26. A rail anchor of channel formation and having a jaw at one end and a resilient rail gripping member adjacent the other end.

27. A rail anchor having a jaw for gripping the rail when the anchor is secured thereto by a transverse movement, said anchor being of channel formation and of varying section whereby the points of strongest section correspond with the points of greatest strain.

28. A rail anchor adapted to be applied to a single rail having a body of channel formation.

29. A rail anchor comprising a looped member embracing one rail flange and having an arm extending from the lower portion thereof for sliding engagement with the opposite rail flange, said looped member being subject to spring tension when moved transversely on the rail base.

30. A rail anchor having a jaw so disposed as to be distorted and to distort a rail flange upwardly when moved transversely thereon.

31. A rail anchor having a resilient jaw so disposed as to be distorted and to distort a rail flange upwardly when moved transversely thereon.

In testimony whereof I hereunto affix my signature in the presence of two witnesses.

BENJAMIN WOLHAUPTER.
